L. McCLEARY

BELL RINGER

Filed Oct. 25, 1919

Inventor:
Linwood McCleary
Attorney:
A. Randolph, Jr.

Patented May 15, 1923.

UNITED STATES PATENT OFFICE.

LENWOOD McCLEARY, OF CHICAGO, ILLINOIS.

BELL RINGER.

Application filed October 25, 1919. Serial No. 333,252.

To all whom it may concern:

Be it known that I, LENWOOD McCLEARY, a citizen of the United States, residing at Chicago, in the county of Cook and State 5 of Illinois, have invented certain new and useful Improvements in Bell Ringers; and I do hereby declare the following to be a full, clear, and exact description of the invention, such as will enable others skilled in 10 the art to which it appertains to make and use the same.

This invention relates to bell ringers and the primary object is to provide an improved bell ringer for locomotives, which is automatic in operation and which will eliminate any possibility of the bell turning over, and thus overcome the danger from such source at railroad crossings.

Another object of the invention is to provide an improved locomotive bell ringer embodying a fluid operated piston operatively connected with the ordinary bell crank and means for automatically cutting off the fluid pressure to the piston when the same has 25 reached a predetermined point.

A further object of the invention is to provide an improved means for adjusting the valve cut off, so that the fluid pressure can be cut off from the piston at any point desired.

A still further object of the invention is to provide an improved locomotive bell ringer of the above character which is capable of attachment to practically all locomotives and will operate in a smooth and dependable manner, which is durable and efficient in use, one that is simple and easy to manufacture and one which can be placed upon the market at a reasonable figure.

With these and other objects in view the invention consists in the novel construction, arrangement and formation of parts, to be hereinafter more specifically defined and claimed, in connection with accompanying 40 drawings, forming a part thereof in which:

Figure 1 is a longitudinal section of the improved bell ringer.

Figure 2 is a fragmentary side elevation of the upper end of the piston rod and coupling head, showing the means for pivotally securing the same together.

Figure 3 is a detail cross section taken on line 1-2 of Figure 1.

Figure 4 is a detail fragmentary vertical 55 section through the bell crank engaging member and coupling head.

Figure 5 is a fragmentary elevation of the bell crank engaging member.

Referring to the drawings wherein similar reference characters designate corresponding parts throughout the several views, the letter "A" designates a cylinder having an inverted cup shaped piston B reciprocally mounted therein, which is provided with the piston rings α so as to form a fluid tight joint 60 between the inner walls of the cylinder and the piston. The cylinder A is provided with a lateral integral extension a' which is provided with a vertical bore a'' for the reception of the valve plunger C which is reciprocally mounted therein. The valve plunger C adjacent its lower end is provided with an annular groove b which is adapted to be brought into and out of alignment with the ports c which communicate with the 65 lower end of the cylinder and the inlet nipple n . The inlet nipple n is internally threaded and is adapted to receive a suitable connection so as to couple the same with the air or steam pipe. The admission of air or steam is controlled by a suitable valve which is positioned adjacent to the engineer, so that the engineer can conveniently open or close the same when necessary. The valve plunger C is provided adjacent its upper end 70 with an annular flange C' which engages a cushioning spring d which is coiled around the valve plunger C and engages the upper end of the annular extension a' . The spring 75 forms a means for cushioning the valve during the lowering movement thereof. The upper end of the cylinder A is open and is provided with a cap J which is held in place by suitable studs k which are threaded in the cylinder and are engaged by nuts j . The 80 cap J is provided with a central bore or opening which slidably receives the piston rod D, which is formed integral with the piston B. The 85

The upper end of the piston rod D has 90 pivotally connected thereto the coupling head F, the lower end of which is bifurcated to receive the reduced end of the piston rod. The reduced end d' of the piston rod and the bifurcated portion of the 95 coupling head F are provided with aligned openings which receive a coupling or pivot pin G one end of which is provided with a head g' . The opposite end of the coupling or pivot pin receives the sleeve h and is engaged by the cotter pin g , which extends 100 through the coupling pin G. The coupling 105

pin G adjacent the head g' is slightly enlarged in diameter and receives the upper end of a connecting link E which has its lower end bent outwardly and downwardly 5 in close proximity to the valve plunger C. The lower end of the connecting link carries the outwardly extending foot e' which 10 slidably receives the slotted upper terminal R of the valve plunger C. The outer end e' and engages the outer surface of the plunger valve C. The upper terminal of the plunger valve C is provided with the 15 adjusting screw e which is held in adjusted position by means of the lock nut f the purpose of which will be hereinafter more fully described.

The upper terminal of the coupling head F receives the externally threaded rod H 20 which is also fitted into the threaded bore of the bell crank engaging member I. The upper end of which is slotted to receive the outer terminal of the bell crank L. The bell crank is of the ordinary construction 25 and is attached to the ordinary locomotive bell in the usual manner.

The bell crank engaging member I is connected to the coupling head F by the threaded rod H, so that the same can be adjusted 30 in relation to the piston and cylinder so as to be attached to a larger or smaller bell and the same is held in position by a lock nut i'.

In the operation of the improved device, 35 the fluid under pressure enters through the nipple and flows around the annular groove b through the ports c and into the cylinder A and under the piston D and forces the same to the upper end of the cylinder which in turn carries the bell crank engaging member I therewith and operates the bell crank L and thus rings the bell. During the raising movement of the piston the foot e' is raised by the link E and engages the lower 40 end of the set screw e and moves the valve plunger C upwardly and thus raises the grooved portion thereof above the ports c and thus cuts off further supply of fluid to the cylinder. The wall of the cylinder 45 A is provided with an exhaust port l which is adapted to register with an exhaust port m provided in the wall of the cylinder so

that when the piston raises, the fluid pressure will be released and the weight of the bell crank causes the return of the piston 55 to its lowered position carrying the plunger valve C therewith, and the grooved portion thereof into alignment with the ports c which again rings the bell.

It will be seen that through the medium 60 of the spring d the lowering movement of the plunger valve C will be cushioned. The lower end of the cylinder is provided with a removable threaded plug K, so that the cylinder can be cleaned when necessary. 65

In practice, I have found that the form of my invention illustrated in the accompanying drawings and referred to in the above description, as the preferred embodiment, is the most efficient and practical; 70 yet realizing the conditions concurrent with the adoption of my device will necessarily vary, I desire to emphasize that various minor changes in details of construction, proportion and arrangement of parts may 75 be resorted to, when required without sacrificing any of the advantages of my invention as set forth.

What I claim as new is:

A bell ringer including a piston, a cylinder for the piston having an outward lateral extension, a plunger valve slidable in said extension and longitudinally of the piston, said plunger valve having a groove, said cylinder having inlet ports through said extension to cooperate with said groove, means on said extension for attachment of a fluid supply pipe, a spring resting on the upper end of said extension, an enlargement on the valve to rest on said spring, said valve having an elongated slot above said enlargement, a follower slidable in said slot, a screw adjustably extending into said slot from the upper end of said plunger valve to limit movement of the follower, a link connected to the follower, a bell engaging connecting means, and a pin fastening said link, connecting means and piston together. 90

In testimony whereof I affix my signature in presence of two witnesses.

LENWOOD McCLEARY.
